UNITED STATES PATENT OFFICE.

EDWARD JAMES, OF EUCLID, OHIO, ASSIGNOR TO THE YOUNGSTOWN SHEET AND TUBE COMPANY, OF YOUNGSTOWN, OHIO, A CORPORATION OF OHIO.

METHOD OF MANUFACTURING FLEXIBLE METAL TUBING.

Original application filed August 5, 1911, Serial No. 642,532. Divided and this application filed July 20, 1923. Serial No. 652,737.

To all whom it may concern:

Be it known that I, EDWARD JAMES, a citizen of the United States, and a resident of Euclid, county of Cuyahoga, and State of Ohio, have invented a new and useful Improvement in Methods of Manufacturing Flexible Metal Tubing, of which the following is a specification, the principle of the invention being herein explained and the best mode in which I have contemplated applying the principle, so as to distinguish it from other inventions.

The present invention relates in general to the manufacture of flexible tubing, and has, as its principal object, the provision of an improved method for the manufacture of flexible metal tubing of the kind that consists of two wires coiled one within the other.

20 The annexed drawings and the following description set forth in detail certain preferred mechanism for carrying out the invention, such disclosed means constituting, however, but one of various mechanical forms in which the principle of the invention may be used.

In said annexed drawings:-

Figure 1 is a side elevation of a machine for carrying out the invention;

30 Fig. 2 is a view partly in section and partly in elevation of a part of the machine, the parts being shown on an enlarged scale, and the section being taken on the plane indicated by line 2-2 of Fig. 1;

35 Fig. 3 is a detail transverse sectional view of a slightly modified form of die detached, the section being taken on the plane indicated by line 3-3 of Fig. 4, and fragments of the friction rolls being indicated;

40 Fig. 4 is a longitudinal horizontal section through the die taken on the plane indicated by line 4-4 of Fig. 3;

45 Fig. 5 is a vertical section taken transversely through one of the wire guides at the place of oil supply communication; and

Figs. 6 and 7 are views similar respectively to Figs. 4 and 3 of another modified form of the die.

50 Referring to the drawings, the machine comprises a suitable frame 1 to which is suitably secured a die 2 which will be here-

after described in detail, a convenient mode of attachment being to screw the threaded shank 32 of the die into the frame.

Rotatably mounted in the frame 1 are two rolls 3-5 which, by means of suitable gears, not shown, may be driven by a power shaft 7. Opposite the respective rolls 3-5 are two co-operative rolls 4-6 which are connected to the rolls 3-5 by gearing, not shown; the rolls 4-6 are carried in a frame 8 which is pivoted on an axis parallel with the power shaft 7 whereby the rolls 4 and 6 are adapted to be moved towards and from the rolls 3 and 5. Interposed between the frame 8 and a hand-wheel 9 is a spring 33 the tension of which is adapted to be regulated by means of said handwheel, whereby the rolls 4 and 6 are thrust toward the rolls 3 and 5 with more or less force. The two sets of rolls 3-4 and 5-6 are designed to feed forwardly two wires, and to force those wires into and through the die 2, and the above described mounting of the rolls 4-6 provides for accommodating the pairs of 75 rolls to different sized wires.

A tube, consisting for reasons of practical construction of two parts 10-11, extends from the rolls 3-4 to the die 2 and serves as a guide tube for the wire which is being forced into the die. The parts 10-11 of the tube are suitably secured at one end in the die 2, while the other ends of said parts are closely fitted in between the rolls 3-4, the passage 16 through the tube being preferably of such shape in cross-section as to contact with the wire which it is guiding in several planes only. The rolls 3-4 are peripherally grooved and the tube is provided at its corresponding end with ridges fitting into these grooves; the tube is thus held against lateral movement and fits into the feed rolls so closely that the passage of fluid out around the wire is prevented. At a point intermediate between their ends, the tube parts 10-11 are secured in a support 12 having a tube 13 for the admission of lubricant; the tube 13 may, if desired, be secured to the frame 1 and serve as a support for the guide tube. The tube 13 is connected by an opening 17 with the passage 16 in the guide tube.

100 By means of this con-

structure of the guide tube and its supports 12—13, lubricant may be forced in around the wire as it progresses towards the die, and yet the tube gives to the wire effective support along its length. It will be understood that the shape of the opening 16 may be of any desired form so long as it contacts with the wire and yet provides a space around the wire; for instance, if round wire 10 is being used, the opening may desirably be triangular, as illustrated. A duplicate guide tube and support is placed between the die and the feed rolls 5—6.

The die itself may be formed in any one of several ways, each of which will effectively coil the two wires in the desired manner. In Figs. 3 and 4 is shown a die which is formed interiorly for part of its length with encircling corrugations 18, into which leads an opening 19 from one of the tubes 10, the corrugations being helically formed. Between the last corrugation 18 and the outer end of the die is a cylindrical bore 20 which is formed without corrugations; into 25 the bore 20, near its inner end, leads an opening 21 which may be either a circular opening, or which may be formed by slotting the die near its end, and into the opening 21 leads one of the two tubes 10.

30 When the die, as shown in Figs. 2 and 3, is used in the machine, a wire X is forced in by the feed rolls 5—6 through the opening 19 and into the first of the corrugations 18, and as the feed of the wire continues, the wire X is coiled around by the corrugations, and at the same time advances forwardly in the die. Simultaneously, a wire W, heavier than the wire X, is forced in by the rolls 3—4 through the opening 21 into the bore 20, the inner wall of which is inclined to 35 conform with the helix of the corrugations 18. As the wire W is being coiled within the bore 20, the coiled wire X is emerging from the corrugations 18 and advances within 40 in the coil of the wire W as the latter is formed. As the coiled wire X advances, it threads itself, so to speak, within the coil of wire W, and the convolutions of the two wires are forced apart and the convolutions 45 of one wire are alternated with the convolutions of the other. The coil of wire X, however, remains of smaller diameter than the coil of wire W, so that it lies substantially within the latter. In this form, the two 50 wires emerge from the die as a flexible tube composed of two wires coiled one within the other but having their convolutions interposed between one another.

55 Figs. 6 and 7 illustrate another form of die. This die has the helical encircling corrugations 18 as in the former die, but instead of the cylindrical bore 20, there is provided a second series of helically formed encircling corrugations 22 into which leads an opening 23 from one of the tubes 10. The

corrugations 22 have a greater diameter than the corrugations 18, and are furthermore more widely spaced apart than are the corrugations 18. In operating the machine with the die shown in Figs. 6 and 7, the smaller 70 wire X is coiled by the corrugations 18 as before, but the larger wire W is positively coiled by the corrugations 22, and because of the separation of those corrugations the convolutions of the wire W are separated 75 during the formation of the coil. The coiled wire W within the die, therefore, practically forms a thread which forces apart the convolutions of the wire X as the latter advances into the coil of wire W. As the two 80 coils then progress together, they emerge from the die as the finished tubing.

85 Although the dies shown both in Fig. 4 and in Fig. 6, as illustrated, are designed to receive the small wire X further from the discharge end of the die than the large wire W, this arrangement may be reversed. In such case, the corrugations of Fig. 4 will be of such diameter as is required for the coil of the outer or larger wire, whereas the cylindrical bore would remain as it is shown. In the die of Fig. 6, the corrugations 22, of what I will call the outer series, would remain as they are shown, but the corrugations 18, of what I will call the inner series, would 90 remain closely spaced, but would be of the same diameter as are the corrugations 22.

95 The die 2, as seen in Figs. 1 and 2, is substantially identical in structure and function with that seen in Figs. 6 and 7, save only that a smooth portion is left at the outer end of the bore of the die, as seen in Figs. 6 and 7, whereas in the die 2 of Figs. 1 and 2 the corrugations 22 extend entirely to the end 100 of the bore.

105 While all of the types of dies illustrated have been shown with the corrugations 18, it is apparent that that portion of those portions of the bore of any of the dies having the corrugations may be made smooth corresponding to the formation of the bore 20 of the die seen in Fig. 4, and the wires may be led in either as shown or through the openings spaced angularly of the die relative to each other. It may also become desirable to push one of the wires as shown by means of feed rolls and to pull the other wire by means of its frictional contact with the wire being pushed.

110 In order to reduce friction and facilitate ease and speed of operation, the die, whether of the form shown in Fig. 1 or Fig. 4, or Fig. 6, or otherwise, is provided with openings 26 which are longitudinal notches or 115 open-ended slots, as best seen in Figs. 3 and 4, proportioned to receive the peripheral portions of friction rolls 27 and 28. The rolls 27 and 28 are preferably spaced, as shown in Fig. 1, the upper roll, 28, being 120 mounted in a frame 29, which frame is 125

mounted to oscillate on a shaft 30 and may be adjusted by the hand-wheel 31 arranged to thrust a spring 34 against the free end portion of the frame 29 with variable force, according to the friction required. The adjustability of roll 28 also allows the machine to be better accommodated to wire of different sizes. The several rolls 27-28 are geared to rotate synchronously by intermeshing gears seen in dotted lines in Fig. 1 and driven from a source of power not shown.

In the operation of the machine, the wires W and X are forced by means of their respective feed rolls into the die 2 as above explained, and the rolls 27-28, extending into the openings 26 of the die, form rolling surfaces for the wires as they are being coiled. Hence, the friction caused by forcing the wires through the die is greatly reduced. Moreover, the rolls 27-28 also exert a pulling force on the wires and thus further assist the feed rolls which are forcing the wires through the die.

The wires W and X have been illustrated and considered as circular in cross section, but they may be of any desired form. It may be desirable to use a large wire W circular in cross section, and to use a smaller wire X triangular in cross section. The present invention is not limited to the manufacture of tubing utilizing circular wires only, but if the shape of the wires is to be different, the die may be slightly changed to conform to the shape of the wire. The main features of construction of the die, however, will remain as before.

Neither is the present invention limited to the use of rolls for forcing the wires into the die, but any other suitable means may be used, it being only necessary that such means be sufficient to force the wires into the die.

Other modes of applying the principle of my invention may be employed instead of the one explained, change being made as regards the mechanism herein disclosed, provided the means stated by any of the following claims or the equivalent of such stated means be employed. This application forms a division of my Patent No. 1,466,999, dated September 4, 1923.

I therefore particularly point out and distinctly claim as my invention:—

1. The method of manufacturing flexible tubing having a plurality of engaging coils of wire, comprising forcing the wires in a tangential direction relative to the formed coils and confining substantially the entire periphery of the last formed convolute of each of the coils during the formation thereof, and forcing the convolutes of an outer coil between the convolutes of an inner coil during such formation, substantially as described.

2. The method of manufacturing flexible

tubing having two coils of wire in which the convolutes of one coil alternate with the convolutes of the other coil and in which the convolutes of one coil exert pressure on the convolutes of the other coil to form tight joints between the convolutes of the two coils, comprising continuously moving the wires in a longitudinal direction and tangential to the convolutes of the coils, confining substantially the entire periphery of the last formed convolute of each coil during the formation of the coils, and also during the formation of one of the coils predetermined its pitch substantially as described.

3. The method of manufacturing flexible tubing having two coils of wire in which the convolutes of one coil alternate with the convolutes of the other coil and in which the convolutes of one coil exert pressure on the convolutes of the other coil to form tight joints between the convolutes of the two coils, continuously moving two coil forming wires of different diameters in a longitudinal direction and tangential to the convolutes of the formed coils, confining substantially the entire periphery of the last formed convolute of each coil during the formation of the tubing to form coils of predetermined diameters, and also during the formation of the coil formed of the wire of greatest diameter predetermined the pitch of said coil so that the convolutes thereof will exert lateral pressure on the convolutes of the other coil substantially as described.

4. The method of manufacturing flexible tubing having two coils of wire in which the convolutes of one coil alternate with the convolutes of the other coil and in which the convolutes of one coil exert pressure on the convolutes of the other coil to form tight joints between the convolutes of the two coils, comprising continuously moving a coil forming wire in a longitudinal direction and tangential to the convolutes of the formed coil, confining substantially the entire peripheries of a plurality of the last formed convolutes of said coil to form an inner coil of predetermined diameter and also controlling the longitudinal movement of a plurality of the last formed convolutes to form convolutes of a predetermined pitch, feeding a second wire of greater cross-sectional area than the first wire in a longitudinal direction and tangential to the convolutes of the formed coil, confining substantially the entire peripheries of a plurality of the last formed convolutes of the last-mentioned coil to form an outer coil whose inner diameter is less than the outer diameter of the inner coil, laying the convolutes of the outer coil between the convolutes of the inner coil, and predetermined the pitch of the outer coil by controlling the longitudinal movement of a plurality of the last formed convolutes of the outer coil to cause

the convolutes of the outer coil to spread the convolutes of the inner coil, substantially as described.

5. The method of forming wire coils, comprising forcing a wire in a longitudinal direction and tangential to the convolutes of the coil, during the formation of the coil confining substantially the entire periphery of the last formed convolute to form a coil

of predetermined diameter, and at the same time controlling the longitudinal movement of the coil along the axis during its formation of the convolutes to form a coil of predetermined pitch, substantially as described.

In testimony whereof I have hereunto set my hand.

EDWARD JAMES.
